CLAIM

The design for a combined pour spout and cap for a container, as shown and described.

DESCRIPTION

FIG. 1 is a front elevation view of a combined pour spout and cap for a container showing my new design, shown with the cap removed for clarity;

FIG. 2 is a longitudinal cross-section view taken along line 2—2 of FIG. 5, shown with the cap removed for clarity of illustration;

FIG. 3 is a front elevation view, the rear elevation view being a mirror image;

FIG. 4 is a right side elevation view thereof;

FIG. 5 is a top plan view, shown with the cap removed for clarity of illustration;

FIG. 6 is a left side elevation view thereof; and,

FIG. 7 is a bottom plan view, shown with the cap removed for clarity of illustration.

The broken line showing of the container and cap in FIG. 3 is for illustrative purposes only and forms no part of the claimed design.
